JOHN C. BEACH, OF SAN FRANCISCO, CALIFORNIA, ASSIGNOR TO LACHMAN WALL BED COMPANY, OF SAN FRANCISCO, CALIFORNIA, A CORPORATION OF CALIFORNIA.

FOLDING BED.

1,249,270.

Specification of Letters Patent.

Patented Dec. 4, 1917.

Application filed May 18, 1915. Serial No. 28,875.

To all whom it may concern:

Be it known that I, JOHN C. BEACH, a citizen of the United States, residing at the city and county of San Francisco and State of California, have invented new and useful Improvements in Folding Beds, of which the following is a specification.

This invention relates to folding beds, and has for its object to improve and simplify 10 the construction and operation thereof.

More particularly, my invention is concerned with providing a folding bed which will be self contained; that is to say, one carried upon its own base whereby it may 15 be readily transferred from place to place in a room or building and made to occupy any available space whether in a closet, recess, or elsewhere. A prime essential of such a bed is that it have a minimum of 20 space requirement. To best effect this, I employ at the outset an extremely narrow base from which no parts are permitted to project when the bed is in folded position thereon. A fulcrum support which will 25 evenly transmit the weight of the bed to the base at all times must be provided and this is in the form of toggle links which fold compactly with the frame, when the latter is in vertical position, and capable of sus- 30 taining the maximum weight requirements, when the bed is in use. Counterbalancing mechanism for the bed-frame which will be light, compact and durable must also be included in the present device. Contractible 35 coil springs are best suited for this purpose, but in prior structures employing similar means, it has been necessary to overload them in order to render them of any benefit in use and consequently they soon wear out.

40 I overcome this objection by an improved arrangement of the counterbalancing springs and the employment of auxiliary lifting springs in connection with the toggle link fulcrum support, whereby the desired force 45 to balance the bed will be exerted by the springs without their being stretched beyond their rated capacity. The head-piece for the bed, which must have a folding movement relative to the frame, has not heretofore 50 been rigidly supported and securely locked when in useful position. The means I employ for pivotally supporting the frame make possible the use of toggle links for

connecting the head-piece with the fulcrum support. This arrangement effectually over- 55 comes the objections noted.

One form which my invention may assume is exemplified in the following description and illustrated in the accompanying drawings, in which—

Figure 1 shows a side elevation of a portion of a bed embodying my invention, the parts being shown in folded position.

Fig. 2 shows a view similar to Fig. 1, with the parts in position for use.

Fig. 3 shows a plan view of one of the base-plates employed in my device, taken on line 3—3 of Fig. 2.

Fig. 4 shows a front elevation of a complete bed structure embodying my invention.

Fig. 5 shows a detail, taken on the line 5—5 of Fig. 2.

Referring now in detail to the drawings and to the form of my device illustrated therein, it will be seen that the complete bed structure comprises, generally, a main frame 10, base-plate 11, fulcrum support 12, and a head-piece 13; the frame being tiltable on the base-plate through its fulcrum support and the head-piece being foldable on the 80 frame. The usual folding legs, not shown, are provided at the foot of the bed for supporting the same in extended position.

The side bars 14 of the main frame are formed of channel iron and at their forward ends are 85 connected together by a transverse plate 15 to which plate are attached bed springs 16 for supporting the mattress or the like. Working within each of the channel bars, near the forward end thereof, is a roller 17, which 90 is shown in Fig. 2 as carried upon the upper end of a supporting leg 18. The leg 18 is also channel-shaped and is pivoted at its lower end 19 to a bearing support 20 carried upon the base-plate 11. The fulcrum 95 link 21 is pivoted to the intermediate portion of the supporting leg and has a pivotal connection 22 with the side 14 of the bed-frame. The link 21 and member 18, in operation, 100 form a toggle joint and constitute the fulcrum support for the bed-frame. When the bed is down in horizontal position the leg 18 assumes the angular position shown in Fig. 2 where it is held against downward movement by a stop 23 formed upon the bearing 20. 105 The toggle links are thus locked against

movement and form a rigid support for the bed-frame.

In raising the bed to vertical position, the frame bar 14 rides upon the roller 17, while 5 the front end of the bed swings with the link 21 as a radius bar to a point where said link is folded within the channel of the leg 18 practically parallel therewith, as shown in Fig. 1. In this position the bed-frame occupies 10 the same angular position as the leg 18 is shown to have in Fig. 2 and further movement of the bed to bring it to vertical position takes place about the pivot 19 of the supporting leg.

15 It is, of course, necessary to counterbalance the bed-frame so that in its pivotal action it will move easily. I provide for this by means of a contractile coil spring 24 connected to each side bar 14, near the front end thereof, 20 and extending downwardly where it is connected at its lower end to a link 25 pivotally carried upon the vertical plate 26 of the base-plate 11. Link 25 is free to move downwardly to the position shown in Fig. 25 1 but is locked in its horizontal position against further movement by means of an adjustable bumper screw 27 seated in the vertical plate 26. The arrangement of the spring 24 is such that when the bed is in 30 horizontal position, said spring is under its greatest tension and tends always to lift the frame to vertical position. However, when the main frame has been swung about its pivot to about the point shown in dotted 35 lines in Fig. 2, the tension of the spring is entirely released and further movement of the frame allows the link 25 to drop downwardly and the spring to assume the position shown in Fig. 1 where it will be seen 40 that both parts are out of the way of the main frame. I find that by carrying the spring 24 upon the folding link 25 I am able to use a longer spring than otherwise and still keep it clear of the other parts of the 45 bed. The spring, I find, can be of such length as to make overstressing unnecessary and the possibility of such a spring losing its elasticity or quickly wearing out is greatly minimized.

50 It will be seen from the description thus far given that the counterbalancing spring 24 comes into use only at the beginning of movement of the bed from horizontal to vertical position and that it exerts no force 55 tending to lift the latter beyond the dotted line position shown in Fig. 2. I find that it is impractical to make any one spring or set of springs working together lift the bed during its entire movement from horizontal 60 to vertical position. To so employ the springs it would be necessary to overload them. I, therefore, make use of an auxiliary lifting or counterbalancing spring 28 which is arranged between the front end of the 65 side bar 14 and the central portion of the

supporting leg 18, being connected at 29 to the frame bar and at 30 to the supporting leg.

As shown in Fig. 2, this spring is under 70 its greatest tension when the bed is in horizontal position and during the initial upward movement of the bed-frame a very slight variation only takes place in the tension of this spring. Beginning at about the point where the spring 24 becomes slackened, the toggle members 18 and 21 will be 75 in such position that the force of the spring 28 will tend to move them into folded position and it is this force which assists in completing the upward movement of the bed-frame from the dotted line position shown 80 in Fig. 2 to the position where the side bar 14 will be in line with the leg 18, from which latter position to the vertical the movement is a comparatively easy one and is accomplished 85 readily without the assistance of springs merely by slight manual effort. When the parts are folded, spring 28, as shown in Fig. 1, lies in the channels of the members 14 and 18 where it is practically 90 hidden from view.

The head-piece 13 is required to be folded into parallel relation with the main frame when the parts are in vertical position and to be held at right angles thereto when the 95 bed is in use. It is found that at times this head-piece will be called upon to sustain great weight and, as arranged in prior structures, this would have a tendency to tilt the frame 10. I overcome this objection and 100 provide a substantial support for the head-piece by employing a bell-crank 31 fastened to a leg 32 of said head-piece and pivoted at 33 to the side bar 14 from which point it projects downwardly, being formed of 105 rigidly connected links 34. To the lower end of the bell-crank lever is pivotally connected a link 35, which in turn is pivoted to the leg 18, upon the pivot pin 30 of the spring 28. The bell-crank lever and link 110 35, in conjunction, form a toggle joint between the head-piece and the leg 18, and by means of them the entire weight of the head-piece is sustained.

Referring to Fig. 4, it will be seen that 115 the head-piece is of the usual yoke construction and is provided with vertical bars 32 at either side. Spindles 36 reinforce the construction of the yoke 13 but do not engage at any point with the transverse plate 120 15 of the main frame. The bars 32 extend downwardly, at the sides of the transverse plate, being spaced therefrom and receiving their support, as indicated, from the bell-cranks 29, one of which is arranged on either 125 side of the bed-frame.

Viewing the position of the parts shown in Fig. 2, it will be seen that the toggle links 35 and 29 are in such position as to form a lock against downward movement of the 130

head-piece 13. In moving the bed structure from horizontal to vertical position, the yoke 13 is maintained in vertical position, although allowed to move downwardly with 5 the front end of the bed-frame. At this time the bell-crank 29 swings around, with the link 35 acting as a radius rod, until it has reached the folded position shown in Fig. 1, which occurs at the time when the 10 frame bar 14 comes into parallel relation with the leg 18. The yoke 13 at this time will not be in vertical position, but assumes such position when the bed structure is rocked to upright position about the pivot 15 19 of the leg support. I preferably provide a stop or rest 37 for each leg of the yoke 13. This is in the form of a block cast on the vertical plate 26 and of such size and so positioned as to sustain the full weight of 20 the head-piece when the bed is in upright folded position. The strain is thus taken off of the pivots of the toggle links.

A ledge 40, formed upon the base-plate 11, is so positioned as to be engaged by the 25 front or lower end of the side bar 14 when the latter is in vertical position and the weight of the bed structure is largely sustained thereby.

Throughout the specification I have described but one side of the bed structure, but, as shown in Fig. 4, the sides are duplicated as to all parts and operate in the same manner, although it is obvious that one-half of the mechanism by being positioned centrally in the bed frame would serve the purpose.

A brief summary of the operation of this device follows: From the upright or folded position of the parts, as shown in Fig. 1, 40 the operator swings the entire structure about the pivot pins 19 of the supporting legs 18 until the latter strike the stops 23, which will be at an angle of about 90° to the horizontal. At this time the weight of 45 the bed will have some influence and a slight pull by the operator will start the frame in its movement about the fulcrum roller 17 and pivoted link 21. As the force of gravity increases, the spring 28 will come into 50 play and check the falling movement of the bed until a point is reached where the spring is stretched practically its greatest distance, which, as shown in the dotted lines in Fig. 2, will be at a time when the spring 24 is 55 brought into position to be placed under tension and check the movement of the bed. The reverse of this operation takes place in the movement of the bed from the horizontal to vertical position.

60 It is called to attention that the base-plates 11, upon which the bed structure is carried, may be positioned at any desired location in a room or building and that no other anchoring or fastening means than 65 screws or bolts 41 are necessary for each of

the base plates. The present structure obviously is well adapted for use in closets or similar recesses. The construction is simple and economical and the same has been shown by actual test to operate with improved ease 70 and facility.

While I have shown and described but one form of my device herewith, it is to be understood, nevertheless, that many changes in construction and arrangement of the several 75 parts thereof may be resorted to without departing from the spirit of my invention as disclosed in the appended claims.

Having thus described my invention, what I claim and desire to secure by Letters Patent is—

1. In a folding bed, the combination of a frame, a base-plate, a swinging fulcrum support slidably connected with said frame and pivoted to the base-plate, and a link connection between the front end of the frame and the fulcrum support operable to limit the relative movement between the parts, said link forming with the fulcrum support a toggle connection to support the head of the 85 bed.

2. In a folding bed, the combination of a frame, a base-plate, a supporting leg pivotally connected to the base-plate and slidably engaged with the frame, a link pivotally connected to an intermediate portion of said leg and to the front end of the frame, and means for limiting the pivotal movement of said leg. 95

3. In a folding bed, the combination of a frame, a base-plate, a supporting leg pivotally connected to the base-plate and carrying a roller at its upper end operating in a channeled guideway on said frame, means on the base plate for limiting the pivotal 100 movement of said leg upon the support, and a link pivotally connecting said leg with the frame to limit the movement between the leg and frame. 105

4. In a folding bed, the combination of a frame, a base-plate, a toggle fulcrum support connecting said frame and base-plate and comprising a leg pivoted to the base-plate and movable with the frame and a pivoted link between the leg and frame, and 110 means acting to fold the members of said toggle when the bed is in slanting position, said means comprising a contractile coil spring connected to the intermediate portion of said leg and to the frame of the bed. 115 120

5. In a folding bed, the combination of a channel bar frame, a base plate, a toggle fulcrum support connecting the frame with the base-plate, said fulcrum support comprising a channel bar leg pivoted to the base-plate and movable within the channel on said frame and a link pivotally connecting the link with the frame, and means acting to fold the members of said toggle when the frame is in slanting position, said means 125 130

comprising a contractible coil spring secured to the forward end of the channel bar frame and to the intermediate portion of the channel bar leg and adapted to lie in the recess 5 in said channel when the parts are in folded position.

6. In a folding bed, the combination of a frame, a base-plate, a toggle fulcrum support connecting the frame and the base-plate, a spring tending to fold the members of said toggle when the frame is in slanting 10 position, and a counter-balancing spring for assisting in the initial folding movement of the frame.

15. 7. In a folding bed, the combination of a frame, a base-plate, a toggle fulcrum support connecting the frame and the base-plate, a spring tending to fold the members of said toggle when the frame is in slanting 20 position, and a counter-balancing spring for assisting in the initial folding movement of the frame, said counterbalancing spring being connected to the front end of the bed-frame and a downwardly movable link carried on the base-plate.

30. 8. In a folding bed, the combination of a tiltable frame, a movable fulcrum support therefor, a counterbalancing spring acting to initially lift the frame from horizontal position, and a second spring connecting the fulcrum support with the bed-frame for completing the lifting movement.

35. 9. In a folding bed, the combination of a tiltable frame, a base therefor, a toggle fulcrum support between the frame and base, a counterbalancing spring between the frame and base to initially lift the frame from horizontal position, and a second spring connecting the fulcrum support with the frame 40 for completing the movement of the latter to a substantially vertical position.

45. 10. In a folding bed, the combination of a tiltable frame, a fulcrum support therefor, a base-plate to receive the fulcrum support for said frame, a link pivotally carried on the base-plate and movable from a pendent to a horizontal position, and a counterbalancing spring connected to said frame and to said link whereby the spring may be folded 50 upon the base-plate when the frame is raised to vertical position to clear the end of said frame.

55. 11. In a folding bed, the combination of a tiltable frame, a base-plate to receive the fulcrum support for said frame, a link pivotally carried on the base-plate and movable from a pendent to a horizontal position, a counterbalancing spring connected to said frame and to said link whereby it may be folded 60 when the frame is raised to vertical position, and adjustable limiting means for said link whereby the tension of the spring may be varied.

65. 12. In a folding bed, the combination of a tiltable frame, a movable fulcrum support

therefor, a folding end-piece for the frame, and a toggle connection between said end-piece and the fulcrum support for sustaining the weight of the former when the bed is in horizontal position.

70. 13. In a folding bed, the combination of a tiltable frame, a movable fulcrum support therefor, an end-piece for the frame, a bell-crank lever connecting the end-piece to the frame, and means connecting the bell-crank lever to the fulcrum support whereby the weight of said end-piece is sustained and the same is maintained in vertical position.

75. 14. In a folding bed, the combination of a tiltable frame, a fulcrum support therefor, 80 an end-piece pivotally connected to the frame and foldable therewith, and means connecting the end-piece and fulcrum support for transmitting the weight of said end-piece when in operative position to the 85 fulcrum support.

80. 15. In a folding bed, the combination of a tiltable frame, a fulcrum support therefor, an end-piece pivotally connected to the frame and foldable therewith, means connecting the end-piece and fulcrum support for transmitting the weight of said end-piece to the fulcrum support when the bed is in horizontal position, and a base-plate to support said end-piece when the bed is in vertical 90 position.

95. 16. In a folding bed, the combination of a tiltable frame, a base-plate, a movable fulcrum support pivoted to the base-plate and connected to the frame, said support being 100 normally inclined from the vertical, and counterbalancing means for swinging said frame pivotally about the fulcrum support from a horizontal to an oblique position to bring the two into parallel relation, said 105 parts being thereupon movable about the pivot of the fulcrum support with the base to complete the movement of the frame to vertical position.

10. 17. In a folding bed, the combination of a 110 tiltable frame, a base-plate, a supporting leg pivotally connected to the base-plate, a pivoted link connecting the supporting leg with the frame, said link and leg forming a toggle joint, means whereby the frame in its 115 movement from horizontal to vertical position is first moved about its pivots on said fulcrum support until the frame and supporting leg are brought to parallel relation, and means whereby the complete movement 120 to vertical position takes place about the pivot of said leg on the base-plate.

125. 18. In a folding bed, the combination of a tiltable frame, a base-plate, a fulcrum support pivoted to the base-plate and having a toggle connection with said frame, means for retaining the fulcrum support in inclined position when the bed is in horizontal position, a counterbalancing spring for assisting in the initial movement of said frame 130

from horizontal to vertical position, and a spring on said fulcrum support adapted to be brought into position for lifting the frame when the counterbalancing spring 5 has completed its work, said last mentioned spring acting to fold the frame into substantially parallel relation with the fulcrum support, said parts being thereupon movable about the pivot of the fulcrum support on

the base-plate to complete the movement to 10 vertical position.

In testimony whereof I have hereunto set my hand in the presence of two subscribing witnesses.

JOHN C. BEACH.
